DESIGN FOR A TRACTOR LOADER ATTACHMENT

John H. Rogers and Herman E. Luebbers,
Fort Dodge, Iowa

Application November 6, 1944, Serial No. 116,156

Term of patent 14 years

(Cl. D14—3)

To all whom it may concern:

Be it known that we, John H. Rogers and Herman E. Luebbers, citizens of the United States and residents of Fort Dodge, Iowa, in the county of Webster and State of Iowa, have invented a new, original, and ornamental Design for a Tractor Loader Attachment, of which the following is a specification, reference being had to the accompanying drawings, forming part thereof, in which:

Fig. 1 is a side elevational view of a tractor loader attachment showing our new design;

Fig. 2 is a side elevational view of our new

design as seen from the side opposite that shown in Fig. 1;

Fig. 3 is a top plan view of the same; and
Fig. 4 is a front view of our new design.

The dotted line illustration of a fragmentary portion of a tractor in Figures 1 and 2 is for illustrative purposes only.

We claim:

The ornamental design for a tractor loader attachment, substantially as shown and described.

JOHN H. ROGERS.
HERMAN E. LUEBBERS.
